APPARATUS FOR CONTACTING SHEET MATERIALS SUCH AS HIDES WITH FLUID

Lambert S. Linderoth, Jr., Ames, Iowa, and William M. Houghton, Marblehead, and David Edgar, Lynn, Mass., assignors to United Shoe Machinery Corporation, Flemington, N. J., a corporation of New Jersey

Application April 3, 1951, Serial No. 219,055

2 Claims. (Cl. 34—163)

1

This invention relates to an apparatus for treating sheet materials, such as hides, by contacting them with fluid, and more particularly to a method of and apparatus for drying hides in which improved conditions of temperature, humidity and other factors may be maintained.

In drying sheet materials such as hides or skins, ducts or tunnels are customarily employed in which air currents are set up to remove moisture from the work. Heretofore, the presence of the work itself, whether in the form of large or small pieces, has interfered with the proper circulation of the fluid and difficulty as well as much expense has been encountered in attempts to secure proper conditions such as of humidity, temperature, regulated variability and/or uniformity. Prior to the present invention, the mode of transporting work of the type herein considered into, out from, or through the duct or tunnel employed often necessitated the manipulation of heavy doors and/or the shifting of the work with consequent restriction or substantial interference with the fluid flow. The nature of prior attempts therefore has been such that continuity of operation has not been possible and this militated against the maintenance of optimum conditions and prevented treatment of as large a quantity of work as would be desired.

It has now been found that the above-mentioned difficulties may be overcome by maintaining the individual pieces of sheet material or hides in planes parallel to the path of the fluid as the work and fluid are moved in contactual relation and preferably but not necessarily in opposite directions within a duct or tunnel, the mode of transporting the work permitting the use of fluid modifying units in those zones of the duct as found advantageous to secure optimum conditions for any given specific treatment.

In accordance with one of its objects, the invention provides a novel work treating method in which pieces of sheet material, such as hides, are maintained in extended condition and transported in contact with flowing work treatment fluid in such a way as to permit a large quantity of work to be treated in a restricted zone and yet afford ample opportunity for the insertion or use of fluid modifying units.

Another object of the invention is to provide an apparatus in which a large number of individual work pieces, such as hides, may be treated by contact with fluid, the construction of the apparatus being such that fluid modifying units may be installed wherever found necessary to maintain optimum conditions of treatment.

2

In the practice of the method as herein illustrated, air is moved in one direction in a given path and sheets of material, such as hides, are consecutively transported in alternate transverse and longitudinal movements with respect to the path of air and maintained in planes parallel to that path as the treatment proceeds.

The invention further provides an apparatus for use in the practice of the above-described method, this apparatus comprising a duct for the passage of work treating fluid in combination with means for transporting hides in extended condition along the duct and in alternately reversed directions transverse to the duct while maintaining each work piece parallel to the path of the fluid.

The invention may be more fully understood from the following description taken together with the accompanying drawings in which

20 Fig. 1 is a diagrammatic and perspective view, drawn to a small scale, of an apparatus in which the present invention is embodied;

Fig. 2 is a plan view, in diagrammatic form, illustrating the mode of treatment of large quantities of work in the apparatus shown in Fig. 1, but drawn to a slightly larger scale;

Fig. 3 is a sectional view drawn to a larger scale and taken along the line III—III of Fig. 2;

Fig. 4 is a perspective view of a portion of the apparatus shown in Fig. 2 but drawn to a larger scale and showing details of construction for supporting, transporting, or moving the individual work pieces in four groups within the duct;

Fig. 5 is a diagrammatic and detail view drawn to a larger scale of a portion of the driving mechanism, the outlines only of some of the mechanism being shown in Fig. 2;

Fig. 6 is a sectional view taken along the line VI—VI of Fig. 5;

40 Fig. 7 is a sectional view drawn to the same scale as Fig. 3 taken across the entire width of the bays at the extreme left of the apparatus as shown in Fig. 2 and looking toward the right with relation to the latter figure;

Fig. 8 is a plan view of the structure shown in Fig. 7; and

Fig. 9 is a view drawn to a larger scale of some of the details shown in Fig. 7.

The present invention may be used in the treatment of various forms of material which are in individual sheets and the invention is particularly adapted for the tannery field in which hides must be dried. It is understood that the term "hides" as used herein is intended to refer to either hides or skins.

The particular embodiment of the invention as disclosed pertains to the use of air as a fluid but obviously other fluids such as liquids could be used and the apparatus may take the form of a vertical structure to suit given conditions without departing from the concepts of the present invention.

Fig. 1 shows a duct 10 having a U-shaped tunnel-like structure both ends of which communicate to a limited extent with a large bay 12. The major portion of one end 13 of the U-shaped structure does not communicate with the bay 12 but passes downwardly through the floor of the bay and is in communication with the outlet of a fan 14. The major portion of the other end of the U-shaped duct 10 similarly passes downwardly at 16 and is adapted to communicate with an exhaust system (not shown). The bay 12 has an end section 18 (Fig. 2) herein termed a "loading" section and an end section 20 termed an "unloading" section.

Spaced along the top or interior of the passage formed by the duct 10 and traversing the same are T bars 22. These are shown merely as lines in Fig. 1 as, diagrammatically, these T bars may be said to support and define groups of hides as the hides are subjected to treatment in the duct. The air from the fan 14 is permitted to pass through the U-shaped duct 10 in a path shown by the dotted lines or arrows in Fig. 1 without any substantial interference with its flow as the arrangement is such that all hides to be treated in the duct are supported in planes parallel to the fluid flow as will be further explained. It is also to be noted that in any given installation fluid modifying devices such as heating units 24 or 26 (Fig. 1) may be installed in divers places such as below any T bar 22 or in the end zone 27 (where no work is suspended) and as found expedient in maintaining proper work treating conditions within localized zones of the tunnel to obtain optimum results. Parallel with the end or fluid zone 27 is an end work zone 29 for transporting consecutive hides from one leg to the other of the duct 10. The T bars 22 are conveniently supported on columns such as columns 30 and 32 (Fig. 4). The end and interior wall 34 of the duct 10 (partially defining the end or fluid zone 27) is provided with a horizontal angle bar 36 (Fig. 4) which cooperates with two of the T bars 22 to support one group of work pieces in the work zone 29. The end zone 27 is for fluid only. One wall of the large bay 12 is provided with two angle bars 38 and 40 (Fig. 2) for support of the first and last group of hides present in the legs of the duct 10 as will further appear.

The method and additional structural details of the invention may more easily be understood by referring in a broad way to the schematic plan of operation and the relative directions in which the work and fluid move. A work piece such as a hide 42 (Fig. 1) is fastened by means of a hook 44 (Fig. 4) or a conventional toggle (not shown) in extended or spread-out condition upon a vertical drying frame 46 in the loading section 18 of the bay 12. This work piece 42 and its supporting frame 46 (and all the consecutively handled frames and work pieces) are caused to follow the path designated by the solid arrows shown in Fig. 1. This path is zig-zag and leads through the end zone 29 whereas the fluid flow path is parallel with the work at all times while in contact therewith and passes through the end zone 27. When a given work piece 42 has trav-

ersed the length (both legs) of the duct 10 it has been dried and is delivered back to the unloading bay 12 (section 20) for removal from its frame 46.

The duct 10 is made up of steel plates the majority of which form the top 48, four parallel and box-like track members 50 and 52 (Fig. 2) as well as two outside walls 54 and two inside walls 56. The top plate 48 has upturned flanges 58 and 60 which are fastened to the track members 50 and 52, respectively. It will be understood that the duct or conduit 10 is provided with a flooring which is not shown. The roof or top plate 48 is supported on I beams 62 and 64 (Fig. 3) running the length of each leg of the U-shaped duct and resting upon the T bars 22. The large bay 12 is not provided with a roof.

It will be noted in Fig. 1 that the flow of work treating fluid represented by the dotted arrows is counter to the general direction in which the work pieces 42 and frames 46 are conveyed. It will also be appreciated that the T bars 22 do not extend the full width of the passage in the duct 10 but that a space 70 is left along each outside wall 54 to permit passage of consecutive work pieces from group to group and also out from and back into the large bay 12 as well as into and out from the end zone 29.

The two outside track members or box-like structures 50 with bottom flanges or tracks extend into the bay 12 along the outside walls 54 and the full length of each of the four track members 50 and 52 is slotted longitudinally and the flanges provide guideways or tracks for wheels 72. The wheels 72 are mounted in pairs on stub shafts 14 each of which is integral with a block 76 and each of the latter serves as a support for a depending bolt 78 attached to the top flange of a box-like section 79 of a carriage 80. There are two opposed carriages 80 in each leg of the duct 10. The sections 79 of each of four carriages 80 are joined by rods 82 and each of these four carriages 80 is provided with a section for each alternate group of work pieces being treated. Two additional carriages 80 are employed at the sides of the large bay 12 and each of these has only one section 79 adapted to reciprocate past the fluid inlet and exhaust ends 13 and 16 of the duct 10 as will further appear.

Angle bars 84 and 85 (Figs. 1 and 8) are provided in sections 18 and 20 of the bay 12 upon which the frames 46 are adapted to be transported manually as well as by mechanical power.

Each frame 46 upon which a work piece 42 may be supported by toggling is provided with two straps 88 which are hooked over a bar 90 provided with a roller 92 at each end. These rollers 92 are adapted to travel on the angle bars 84, 85, 36, 38 and 40 and also the flanges of the T-bars 22. The angle bar 94 (Fig. 2) also serves as a track for the rollers 92 at one side of the end work zone 29.

The carriages 80 in the legs of the duct may consist of as many sections 79 as found essential in a given installation. This number may vary depending upon the nature or extent of the work to be performed. Each section 79 is provided with two holes 98 and two narrow shelf portions 100 with depressions to receive the rollers 92.

Pulleys 102 are mounted in cooperative sets of four on pins 104 depending from the roof 48 of the duct or (in the case of the four pulleys 102 to the left of the bay 12 in Fig. 2) from superstructure not shown. Each of the two single section

carriages 80 for the bay 12 is connected to one of two flexible driving bands 106 passing around pulleys 102. Each of the four multiple section carriages 80 is connected to a flexible driving band 108 also supported by pulleys 102 and two of these carriages for one leg of the duct 10 are connected to one band 108 and the other two for the other leg are connected to a second band 108. Conveniently, the ends of each band 106 or 108 may be connected to its carriage by a clamp 110 on one of the sections 79 as illustrated in Fig. 4. Opposed carriages in each leg of the duct are connected to the same band 108 to move therewith and in opposite directions in that leg as guided by the track members 50 and 52.

Power for both lateral and longitudinal movement of the consecutive frames 46 through the duct 10 in the path of the solid arrows in Fig. 1 is provided by a geared driving mechanism indicated generally as A in Figs. 2 and 5. This mechanism comprises a shaft 114 which is driven by suitable pulleys and belts 116 (Fig. 5) from a source of power (not shown). This shaft 114 is journaled at 118 and 120 in a casing 122 enclosing the mechanism A. The shaft 114 has a sprocket 124 (Fig. 5) and two gears 126 and 128 pinned to the shaft to revolve with it. The sprocket 124 is arranged to drive a chain 130 which in turn drives a chain 132 by means of sprockets 134 and 136 on a supporting shaft 138, the latter being journaled on the casing 122. The chain 132 is utilized to drive a two-part cam 140 arranged for controlling a one-revolution clutch arrangement. The cam 140 is free to rotate on and relative to the constantly driven shaft 114 and is retained in position by two collars 141 and one portion of the cam 140 bears a cam surface 142 for contacting a roller 144 attached to an arm 146 which is rotatable on a fixed shaft 148. One end of the arm 146 terminates above a shaft 150 to which is keyed an annular member 152. The shaft 150 is arranged to rotate in bearings 151 and 153 formed as parts of the casing 122. The gear 126 is arranged to engage and drive a larger gear 154 which is free to rotate on the shaft 150 with the rotation of the latter being dependent upon the operation of a one-revolution clutch of which member 152 is a part. The gear 154 is provided with internal teeth 158. The annular member 152 is bored to receive a rotatable cylindrical member 160 having a flat portion with an edge 161 adapted to engage the teeth 158 dependent upon rotation of the member 160. The member 160 is provided with a finger 162 integral therewith and protruding from a recess in the hub of the annular member 152 and adapted to engage the end of the arm 146. A spring 164 is mounted on the member 152 to bear against the pin or finger 162 with a tendency to bias the member 160 into such position by engagement of the finger with the end of the arm 146 that the member 152 and the shaft 150 will not be driven by the constantly driven gear 154.

An arm 166 (Fig. 5) is also mounted on the shaft 148 and is similar in construction to the arm 146 but with a roller 170 in position to engage a cam surface 172 on the member 140. The gear 128 is arranged continuously to drive a larger gear 174 on and with respect to a supporting shaft 176 which is mounted in journals 177 and 179 in the casing 122. The gear 174 is arranged to drive the shaft 176 intermittently through internal teeth 171 dependent upon the

operation of a second one-revolution clutch in the same manner as in the case of the shaft 150.

The shaft 150 is provided with a sprocket 180 which drives a chain 182 and a crank member 184 (Fig. 2) to reciprocate a rod member 186. This constitutes a means for driving or transporting the consecutive frames transversely or laterally of the passage for the fluid through the duct or tunnel as well as in the sections 18 and 20 and the zone 29 as will further appear. The rod 186 (Fig. 2) is pivoted to one arm of a lever mechanism 188 which in turn serves to oscillate the ends of rocking levers 190, 191, 192 and 193, as shown in Fig. 2. These rocking levers operate together in proper timed relation to a longitudinal movement of the consecutive frames through the tunnel or duct as will further appear. An arm of each rocking lever 190, 191 or 192 is provided with a slot (Fig. 4) for receiving a pin 194 attached to the end of a push rod 196. Each push rod 196 is arranged to slide or reciprocate endwise in a boss 198 attached to the wall structure of each leg of the duct and is adapted at the proper moment to enter one of the holes 98 in a corresponding carriage 80. It will be noted that there are two rods 196 for each section 79 of a given carriage and that the sets of two rods are in staggered relation along the fluid path. Each rod 196 is in alignment with a row of rollers 92 as they rest upon the flanges of the T bars 22 and the narrow portions 100. The rocking levers are connected to the lever mechanism 188 by rods 195, 197, 199 and 200. The rocking lever 191 is provided with three arms whereas lever 193 has two arms.

The shaft 176 (Fig. 5) is arranged to drive five shafts 201 (Figs. 2 and 5) from a sprocket 202 by means of a series of chains 204, 206, 208, 210, 212 and 214 with suitable cooperating sprockets. Fig. 2 shows a portion of this driving mechanism in a diagrammatic manner. It will be appreciated that the mechanism will be varied to suit the number, arrangement, rate and length of travel of the carriages as required for a given installation.

The chains 208 and 210 (Fig. 5) are arranged to drive the links 216 and 218 back and forth in horizontal relation to the duct. The other ends of the links 216 and 218 are each pivoted to a section 79 of a carriage 80 and the arrangement is such that the opposed carriages in each leg of the duct 10 may simultaneously be driven in opposite directions by virtue of one of the two flexible bands 108. Only one link 216 or 218 is required for each set of opposed carriages 80 in each leg of the duct.

The shafts 210 are arranged to drive the endless chain 214 (Fig. 2) through sprockets 222, 224 and 226. A slide member or bar 230 is rigidly mounted with relation to the superstructure of the duct and a crosshead 232 is mounted to slide thereon in a horizontal direction. This slide member is pivotally connected by a link 234 to the chain 214 so that rotation of the chain 65 causes the crosshead 232 to reciprocate on the bar 230. The two flexible bands 106 are clamped at 236 to the crosshead 232 to move therewith and each band 106 is attached to a one-section carriage 80 which is adapted to reciprocate to 70 and from the bay 12 and into and away from the first or last group of drying frames in the duct legs as will further appear.

A protective covering 204 is used for each of the links 216 and 218 as it may be necessary as a protection for an operator who may desire to

enter the space between the duct legs for lubricating or otherwise servicing the mechanism.

Fig. 3 shows a full group of frames extending in spaced and parallel relation across one leg of the duct. In that figure the left-hand, one-section carriage 80 has been unloaded by the proper push rods 196 acting against the wheels 92 of the first frame. The preceding frames of that group are simultaneously pushed to the right and one section of the right-hand carriage 80 is loaded with one frame the wheels 92 of which roll into the recesses of the narrow shelf portions 100 made to receive them. The right-hand carriage 80 of Fig. 3 then moves counter to the path of the air into the position shown in Fig. 2 where it is to be unloaded by action of two push rods 196 connected to two rocking levers 192 (only one of these two being shown in Fig. 2). While the last-mentioned action occurs the left-hand carriage (Fig. 3) travels back into section 18 of the bay 12 to receive a newly loaded frame from those stored there.

To assist the operators in providing loaded frames at a determined rate but with some leeway for variations, the bay 12 is provided with a mechanism for receiving empty frames as consecutively discharged from the conveyor system into section 20 of that bay, pushing them into a group within convenient reach of the operators and urging them individually, after loading, and in proper timed sequence to the left-hand carriage 80 of Fig. 3. This mechanism is illustrated in Figs. 7, 8 and 9.

In Fig. 8, one wall 54 of the duct is shown provided with a bracket 250 (not shown in Fig. 7) for supporting one of the rocking levers 192 pivotally attached to the rod 200 to actuate a push rod 196. A second rocking lever 192 (for the bay 12) is also pivoted to the rod 200 to actuate a second push rod 196. These two push rods 196 cooperate in unloading treated work from the corresponding carriage 80 giving the operator or operators time to detach the work from each consecutive frame as it rests upon the angle bars 84 and 85. The second lever 192 referred to is pinned to a vertical shaft 252 supported on a bracket 254 attached to the duct. Also pinned to the shaft 254 is an arm 256 having a slot-and-pin connection to a bar 258. The pin of the connection is fixed to the bar 258 which is adapted to reciprocate in directions transverse to the duct. Each end of the bar 258 is provided with wheels 260 having flanges extending into and being guided by elongated openings 262 and 264 in a plate 266 fixed to a track member 50. Beneath the plate 266 and attached to the bar 258 is a longer bar 270 (Fig. 2) extending across the major width of the bay 12 and the left end (Fig. 8) is attached to a block 272 carrying flanged wheels 274 guided by an opening 276 in a plate 278 fixed to a track member 50. The upper ends of four parallel links 280 are pivoted on pins 284 and 286 passing through the bar 270. The lower ends of the links 280 are pivoted to a pair of pusher plates (not shown) but each of which is similar in function and construction to a pusher plate 288 (also one of a pair) partially shown in Fig. 9. The pusher plate 288 is provided with five downwardly extending projections and each projection has a vertical or pusher side 290 and an inclined side 292.

In Figs. 7 and 8, the wall 54 is also shown as being provided with a bracket 296 for supporting a vertical pin or shaft 298. Pinned to the lower end of the shaft 298 is a lever 300 which is

pivotedly connected to the rod 200. Pinned to the upper end of the rod 298 is a lever 302 the end of which is connected by a bolt 304 to a bar 306 which is similar to the bar 258. The bar 306 is provided with four flanged wheels 308 which are guided by a slotted plate 310 similar to the plate 266. A bar 312 (similar to bar 270) is located with one end bolted at 314 to the bar 306 to be carried thereby. The other end of the bar 312 is supported on rollers or wheels 316 resting on a plate 318. The bar 312 carries four pivoted links 320 (like links 280) which are connected to a pair of pusher plates 288 previously referred to. The vertical pusher sides of each of the four pusher plates are spaced a distance at least equal to the diameter of the rollers 92.

Each of the angle bars 84 and 85 have inclined slots such as slots 321 (Fig. 9) to accommodate springs or stop members 322, the ends of which may yield as the rollers 92 pass to the left as viewed in Fig. 9 but which bear against the rollers to prevent their displacement toward the right.

In using the apparatus herein disclosed, assuming the driving mechanism A is being driven by the belts 116 (Fig. 5), the operators in bay 12 manually roll an empty frame 46 from the unloading section 20 of the bay to the loading section 18 and mount a work piece 42 upon that frame in a conventional manner as by the use of toggles or hook 44. The operators may store (preliminary to treatment) a large number of loaded frames 46 in section 18 if they so desire, and section 20 may contain several empty or unloaded frames as well as frames from which the dried hides are to be removed. As the opposed carriages 80 move in alternately reversed directions longitudinally in each leg of the duct 10 the consecutively loaded frames are moved from the work loading section 18 of the bay 12 and caused to follow the path indicated by the solid arrows in Fig. 1. The motion of each loaded frame 46 along the enclosure or duct is effected by operation of the clutch driving the gear 202 (Fig. 5) which causes the carriages 80 simultaneously and intermittently in proper timed sequence to move the appropriate distances and directions for advancing the frames from group to group. The operation of the two one-revolution clutches is such that when the longitudinal stroke (forward or backward) for a given carriage 80 is completed, the push rods 196 are actuated and become effective to unload or load that carriage into or from alternate groups as those groups are arranged on the angle bars 22 or tracks for supporting the wheels 92. Each of the rods 196 completes one forward and one backward thrust in a given actuation through the clutch member 152 with the result that the frames of each group are moved laterally or transverse to the duct to permit introduction into that group of a new frame from a preceding group while one frame is moved longitudinally therefrom. The carriages 80 then perform a longitudinal stroke to be in positions in which the empty sections 79 may be filled and the opposed sections 79 may be emptied as a preliminary to the next longitudinal stroke.

It will be understood that when two opposed carriage sections 79 are stationary and in the same grouping of frames, one of those sections will be unloaded or emptied and the other will be loaded or filled due to the operation of the appropriate push rods 196. All the push rods 196 are simultaneously operated and their momentary impact with the rollers 92 which come into

their paths causes the frames to advance in a direction transverse to the duct or the air path and the frames in adjacent groups to be moved in opposite directions. The rods 196 are so operated that they are withdrawn from the carriage 80 to permit the latter subsequently to move longitudinally of the duct. The timing of the operation of the push rods 196 so that it is intermittent with the movement of the carriages 80 is accomplished by the two cam surfaces 142 and 172.

When the consecutively presented and loaded frames have been transported in the direction shown by the solid arrows in Fig. 1 they are returned to the bay 12 but into the unloading section 20 thereof and the dry hides are removed from the frames as they come to the fore and as convenient in that section. The apparatus disclosed in Figs. 7, 8 and 9 is for the purpose of advancing the frames discharged into section 20 to the left (Fig. 7) by power as an aid to the operators. This shifting of the work in the bay 12 may be by hand but it is conveniently and more easily performed by operation of the appropriate push rods 196 and the plates 288.

The loaded frames 46 in the loading section 18 are intermittently urged to the left (Fig. 7) by the plates 288 the vertical surfaces 290 (Fig. 9) of which are adapted to contact the rods 90. When the horizontal rods 270 and 312 reciprocate, the plates 288 intermittently ride or slide over the rods 90 present in section 18 because of the inclined surfaces 292 and the pivoting of the links 280 and 320. A stop device 330 (Fig. 7), attached to the bar 312, may be employed to prevent the links 320 and the plates 288 from dropping too low in the absence of any or sufficient supporting rods 90 in the section 18 and the bar 270 is similarly provided with a stop member (not shown).

Having described our invention, what we claim as new and desire to secure by Letters Patent of the United States is:

1. Apparatus for subjecting hides to fluid comprising a duct with a bay having a loading sec-

tion and an unloading section, said duct leading from and returning to said bay, means for forcing fluid along and within said duct, means for supporting hides in extended condition and in spaced and parallel relation in said duct, and means for transporting said supporting means from the loading section along the duct and to the unloading section and in alternately reversed directions across the duct, said transporting means including guiding means for maintaining the hides in planes parallel to the fluid flow.

2. Apparatus for subjecting hides to fluid contact comprising a loading and unloading section with a U-shaped duct connecting the two sections, means for forcing a gaseous fluid along and within said duct, means for transporting hides from the loading section and through said duct counter to the fluid, said transporting means including means for holding the hides in extended condition and in planes parallel to the direction of the fluid flow, and said transporting means also including power operated means for shifting the hides in alternately reversed directions across said duct.
